UNITED STATES PATENT OFFICE.

LEONARD F. FULLER, OF SAN FRANCISCO, CALIFORNIA, ASSIGNOR TO FEDERAL TELEGRAPH COMPANY, OF SAN FRANCISCO, CALIFORNIA, A CORPORATION OF CALIFORNIA.

RADIOTELEGRAPHY.

1,339,191.

Specification of Letters Patent. Patented May 4, 1920.

Application filed September 4, 1917. Serial No. 189,523.

To all whom it may concern:

Be it known that I, LEONARD F. FULLER, a citizen of the United States, and a resident of the city and county of San Francisco and State of California, have invented certain new and useful Improvements in Radiotelegraphy, of which the following is a specification.

The invention relates to means of signaling and particularly to means of signaling with arc radio transmitters.

An object of the invention is to provide means for signaling involving interrupting and reestablishing the arc.

Another object of the invention is to provide means for interrupting and reestablishing the arc by varying the length of the arc gap.

The invention possesses other advantageous features, some of which, with the foregoing, will be set forth at length in the following description where I shall outline in full that form of the invention which I have selected for illustration in the drawing accompanying and forming part of the present specification. It is to be understood, however, that the invention as expressed in the claims is not limited to the specific embodiments shown in the drawing.

The drawing is a diagrammatic representation of the signaling system of my invention.

The transmission system comprises an arc oscillation generator, including the electrodes 2-3 between which the arc is formed. One of the electrodes, preferably the negative electrode 3, is grounded and the other electrode 2 is connected to the antenna 4 through the variable inductance coil 5. Direct current is supplied to the arc radio generator by the generator 6 and a choke coil 7 is arranged in the lead 8 which is connected to the electrode 2. The arc is subjected to a strong transverse magnetic field produced by the magnet coils 9 which may be separately excited or arranged in series in the lead 8.

Signaling is accomplished by igniting the arc and subsequently extinguishing it by increasing the distance between the electrodes, and the distance is preferably increased by moving one of the electrodes. In operation, the length of the arc gap is increased to such distance that the arc goes out and subse-

quently the length of the gap is decreased to 55 its proper oscillating arc length and the arc is reestablished by a spark or other means. These operations are performed automatically and at telegraphic speed, and signaling is accomplished with a transmission key 60 in the usual manner.

Secured to the electrode 2 and insulated therefrom is a solenoid core 12 which is movable in a direction to increase the length of the arc gap by a spring 13 and is movable 65 in the opposite direction by the effect of the current flowing in the solenoid 14. The solenoid is arranged in series with a battery 15 and the signaling key 16, which, when depressed, closes the circuit and causes the 70 electrode 2 to be moved to shorten the arc gap to its proper oscillating arc length. An ear projection 17 on the core 12 contacts with a stop 18, as the core moves forward, and stops the electrode 2 so that the proper 75 oscillating arc gap is produced. A stop 19 halts the movement of the electrode on its backward movement. As the electrodes wear, the length of the arc is adjusted to preserve the proper oscillating length by a nut 80 21 engaging the screw 22 secured to the normally stationary electrode 3. The nut 21 is disposed between stops 23, so that the electrode is moved longitudinally by rotation of the nut. 85

I have shown one means for reigniting the arc after the length of the arc gap has been decreased to the proper oscillating arc length. Connected across the arc is a spark circuit containing the spark gap 24, the secondary of the transformer 25 and the capacity 26, shunting the secondary. A stopping resistance 27 is arranged between the spark gap and the antenna side of the arc to prevent direct current sufficient to maintain 95 an arc across the gap 24 from following the radio frequency current across the spark gap and passing through the secondary. The primary of the transformer is in series with an alternating current generator 28 and a 100 switch 29 connected to and insulated from the key 16. When the key is closed, the electrodes are brought together and simultaneously, the circuit through the primary of the transformer is closed, producing a 105 high potential in the spark circuit and producing a spark across the spark gap which sets up radio frequency surges which ignite

the arc. When the key is released, the spring 13 increases the length of the arc gap and causes the arc to be extinguished.

I claim:

5 1. An arc system for radio signaling, comprising two electrodes, means for maintaining an arc between said electrodes, means for increasing the distance between the electrodes to such length that the arc is 10 extinguished and means for reestablishing the arc.

2. An arc system for radio signaling, comprising two spaced electrodes, means for producing a voltage of sufficient magnitude 15 to maintain an arc between the spaced electrodes, means for increasing the distance between the electrodes to such length that the arc is extinguished, means for decreasing the distance between the electrodes and 20 means for producing a voltage of greater magnitude between the electrodes for reestablishing the arc.

3. An arc system for radio signaling, comprising two electrodes, means for maintaining an arc between said electrodes, means for increasing the distance between the electrodes to such length that the arc is extinguished, means for decreasing the length of the arc gap to the proper oscillating 25 arc length, and means for igniting the arc between the electrodes so spaced.

4. An arc system for radio signaling, comprising two electrodes spaced apart a greater distance than the proper oscillating 35 arc length, means for decreasing the distance between the electrodes to proper oscillating arc length and means for establishing an arc between said electrodes so spaced.

5. An arc system for radio signaling, comprising two electrodes spaced apart a greater distance than the proper oscillating arc length, means for decreasing the distance between the electrodes to proper oscillating arc length and means operative simultaneously 40 with the decrease of arc length to the proper length for igniting the arc.

6. An arc system for radio signaling, comprising two electrodes spaced apart a greater distance than the proper oscillating 50 arc length, means for decreasing the distance between said electrodes to proper oscillating arc length, means for igniting the arc between the electrodes so spaced and unitary means for controlling the electrode moving 55 means and the arc ignition means.

7. An arc system for radio signaling, comprising two electrodes spaced apart a greater distance than the proper oscillating arc length, means for moving one of said electrodes to decrease the distance between the electrodes to proper oscillating arc length, means for igniting the arc between the electrodes so spaced and a key arranged to simultaneously operate both of said means. 60

8. An arc system for radio signaling, comprising two electrodes spaced apart a greater distance than the proper oscillating arc length, a spring tending to hold said electrodes apart, a solenoid, a core attached 70 to one of said electrodes and associated with said solenoid, the energizing of the solenoid circuit operating to move said electrode toward the other.

9. An arc system for radio signaling, comprising two electrodes spaced apart a greater distance than the proper oscillating arc length, a spring tending to hold said electrodes apart, a solenoid, a core attached 75 to one of said electrodes and associated with said solenoid, the energizing of the solenoid circuit operating to move said electrode toward the other, and means for stopping the movement of the electrode when the distance between the electrodes is equal to the proper oscillating arc length.

10. An arc system for radio signaling, comprising two electrodes, means for maintaining an arc between said electrodes, means for increasing the distance between the electrodes to such length that the arc is extinguished, means for decreasing the distance between the electrodes, and means for producing a spark between the electrodes so spaced whereby the arc is reestablished. 90

11. An arc system for radio signaling comprising two electrodes between which an arc is formed, an antenna circuit connected to said electrodes, means for increasing the distance between the electrodes whereby the arc is extinguished, means for decreasing the distance between the electrodes and means for producing radio frequency surges in the antenna circuit which reignite the arc. 10

In testimony whereof, I have hereunto set my hand at San Francisco, California, this 27th day of August 1917.

LEONARD F. FULLER.
